UNITED STATES PATENT OFFICE

128,314

DESIGN FOR A COUPLING OR ANALOGOUS ARTICLE

John T. Kelly, Chicago, Ill.

Application March 1, 1941, Serial No. 99,277

Term of patent 14 years

To all whom it may concern:

Be it known that I, John T. Kelly, a citizen of the United States, residing at Chicago, in the county of Cook and State of Illinois, have invented a new, original, and ornamental Design for a Coupling or Analogous Article, of which the following is a specification, reference being had to the accompanying drawing, forming a part thereof.

In the drawing—

Fig. 1 is a front perspective view of a coupling or analogous article showing my new design;

Fig. 2 is a front elevational view of the same, and

Fig. 3 is a side elevational view of the same.

I claim:

The ornamental design for a coupling or analogous article, as shown.

JOHN T. KELLY.
